(57) **CLAIM**

The ornamental design for an electrical power connector, as shown and described.

DESCRIPTION

FIG. 1 is a bottom, left, front perspective view of an electrical power connector according to our design;

FIG. 2 is a top, right, rear perspective view of thereof;

FIG. 3 is another bottom, left, front perspective view thereof;

FIG. 4 is a bottom, left, rear perspective view thereof;

FIG. 5 is a top, left, rear perspective view thereof;

FIG. 6 is a bottom, right, front perspective view thereof;

FIG. 7 is a front elevation view thereof;

FIG. 8 is a rear elevation view thereof;

FIG. 9 is a left side elevation view thereof;

FIG. 10 is a right side elevation view thereof;

FIG. 11 is a top plan view thereof; and,

FIG. 12 is a bottom plan view thereof.
